Primary Examiner — Patricia A Palasik(74) *Attorney, Agent, or Firm* — Frank Gao, Esq.(57) **CLAIM**

The ornamental design for a base plate of warehousing robot, as shown and described.

DESCRIPTION

FIG. 1 is a first perspective view from the front and to the right of a base plate of a warehousing robot, which is subject of the present design;

FIG. 2 is a second perspective view thereof from the rear and to the left;

FIG. 3 is a third perspective view thereof from below and to the left;

FIG. 4 is a front view thereof;

FIG. 5 is a rear view thereof;

FIG. 6 is a left side view thereof;

FIG. 7 is a right side view thereof;

FIG. 8 is a top plan view thereof; and,

FIG. 9 is a bottom plan view thereof.
